INVENTOR:

Hiram N. Sheek.

By E. A. Silvius.

ATTORNEY

UNITED STATES PATENT OFFICE.

HIRAM N. SHEEK, OF GREENWOOD, INDIANA.

FLY-EXIT FOR SCREENS.

SPECIFICATION forming part of Letters Patent No. 643,335, dated February 13, 1900.

Application filed May 29, 1899. Serial No. 718,665. (No model.)

To all whom it may concern:

Be it known that I, HIRAM N. SHEEK, a citizen of the United States, residing at Greenwood, in the county of Johnson and State of Indiana, have invented certain new and useful Improvements in Fly-Exits for Screens; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to a fly-exit device adapted to be applied to either new or old screens for windows and doors and to those of various widths; and it consists in an inclosure of a new and novel form in which the 20 flies may move about leisurely in their passage from the room and provided with extensible leadways thereto and also with an exit to project through the screen; and it consists, further, in the parts and combination and arrangement of parts hereinafter fully described and claimed.

The object of this invention is to provide a device of this character that may be attached permanently to the screen when the same is 30 first made or which may be as readily applied afterward and to various sizes of screens.

A further object is to provide such a fly-exit as shall be most effective in alluring flies from a room and which may be cheaply made 35 and be durable and economical in use.

I attain these objects in my invention shown herein.

Referring to the drawings, Figure 1 represents a perspective view of a diminutive window screen and frame in which is illustrated my invention applied thereto; Fig. 2, an elevation of the outer side; Fig. 3, a central vertical transverse sectional view; Fig. 4, an elevation of the inner side, and Figs. 5 and 6 45 fragmentary detail views.

Similar letters of reference in the several figures of the drawings designate similar parts.

In practically carrying out my invention I provide what may be termed an "inclosure" 50 C, which is small as compared to the superficial area of the screen. It is suitably composed of tin-plate painted or of other similar

metal or of pressed strawboard or the like and comprises a bottom h, a short back J, having at each end a curved extension O, at the outer end of which is an ingress in the side of the inclosure, a front, and sides converging toward the top e, at which is a conical tubular exit E, projecting from the line of the flanges b, corresponding to the back, which is otherwise open as constructed, but which is practically closed by the screen, against which it may be placed and to which it may be secured by soldering or in any other suitable manner. The inclosure may be built up as 65 it appears or it may be stamped out or pressed from a sheet in a single piece. The sides are preferably vertical for a short distance and then lead conically to the exit at the top, so that a fly in its invariably upward movement 70 in crawling will eventually reach the exit and escape to the outside, but, as is well known, will not enter a small tube projecting from a surface upon which it may be.

The leadways D D' are essentially alike, 75 differing only in that one is adapted to the right side and the other to the left-hand side. They each comprise a longitudinal portion vertical to the screen, an overhang flange k, and a base-flange d to bear against the screen. 80 They are attached at opposite ends of the bottom h, but to the sides of the inclosure, so as to be above the open ingress-channel F in the sides formed by the curved back O, the open inner end of which is a little distance from 85 the side of the inclosure, so that a fly may not be inclined to return therethrough. The construction is such that a fly alighting upon the screen would naturally crawl upward, as indicated by the arrows, until arriving at a leadway, each of which extends from the inclosure-ingress downward at a suitable angle to the edge of the screen, when it would follow the leadway up to and enter the inclosure through the channel F and finally wander upward in the inclosure until the exit is reached. 90 When the device is intended to be applied to old screens or interchangeably, I provide extensions D² for the leadways D D', preferably comprising a vertical part and overhang and base corresponding to the main leadway, but having a turned-over edge m, forming a slip-joint, thus being adjustable to frames of differing widths. As a further ingress to the 95

inclosure I provide an open way I below a vertical slide-door G, having a lip g resting normally upon the tops of the guide-cleats f. The door may be further raised and removed, 5 if desired, to expose a larger opening I' in the front of the inclosure to gain access to place sugar or fly-poison into the part i, divided off as a receptacle by a vertical partition II in order to attract the flies thereto.

- 10 The whole device may be attached by means of the beads or cleats a, which are usually employed to secure the screen to the usual frame A and as a facing, the flanges b d d' being suitably adapted for this purpose, and they also afford a surface for soldering, but may be dispensed with and other suitable means employed instead whereby to secure the device.

It will be obvious that the inclosure may be formed of wire-netting or perforated metal, 20 but I preferably employ imperforate sheet metal, as then the light would enter from the outside of the building and attract the fly to proceed outward, particularly when the room of the building is darkened somewhat. The 25 bottom h may be constructed so as to be depressed at the center, if desired, so as to lead an approaching fly at the outside upward and across to the end and channel F.

The advantage in providing the inclosure 30 is in permitting a fly after entering it to have sufficient freedom of movement to avoid its noticing that it is entrapped against returning, so that it may leisurely continue onward and upward instead of dashing about in excitement and warning others away in an effort to return, and it is obvious that the exact form shown need not be adhered to in construction within the scope of my invention. The inclosure may be provided with a 35 permanent perforated back; but the screen suitably provides this.

Having thus described my invention, what I claim as new, and desire to secure by Letters Patent, is—

45 1. A fly-exit device provided with an inclosure comprising a close bottom, a front and sides, all formed up so as to provide a compartment wherein the flies may be at ease, ingress-openings formed at the sides above the bottom and ingress-channels having their 50 walls projecting into the interior of the inclosure, a leadway at each of the ingress-channels, and an exit from the inclosure.

2. A fly-exit device comprising an inclosure 55 struck up from sheet material so as to provide a bottom, a front and short vertical sides above which are continuing sides converging at the top, an ingress-channel having the walls thereof projecting inwardly from each 60 of the vertical sides above the bottom, leadways extending from the ingress-channels, and an exit from the inclosure.

3. A fly-exit device comprising an inclosure, 65 an exit from the inclosure, an ingress-opening at each side of the inclosure above the bottom thereof and provided with a channel having the walls thereof projecting inwardly

from the ingress-opening, and leadways connected above the ingress-openings.

4. A fly-exit device comprising an inclosure, 70 an exit from the inclosure, an ingress to the inclosure at each side and above the bottom thereof and provided with a channel having the walls thereof projecting inwardly from the ingress-opening, leadways connected above 75 the ingress-openings, an ingress in the front at the bottom of the inclosure, and a slide-door partially covering the ingress at the front of the inclosure.

5. In a fly-exit, the combination of the 80 screen, the inclosure secured to the screen and consisting of a bottom, a front and short vertical sides continuing and converging to the top; a partition rising from the bottom; an ingress at the front of the partition in the 85 front of the inclosure; an ingress in each of the vertical sides above the bottom of the inclosure; an ingress-channel having the walls thereof projecting inwardly from each ingress-opening at the sides, a leadway connected to each of the vertical sides above the 90 ingress-openings, and an exit from the inclosure.

6. In a fly-exit, the combination of the 95 screen, the inclosure comprising an imperforate front and bottom and sides and top and secured to the screen, an ingress-aperture in the front of the inclosure at the bottom thereof, a partition within the inclosure extending above the ingress to provide a trap against 100 return through the ingress-aperture, an ingress-channel at each side of the inclosure and extending inwardly therefrom, leadways extending from the ingress-channels at the 105 sides of the inclosure, and an exit at the top of the inclosure, substantially as set forth.

7. In a fly-exit device, the combination of 110 the screen, the inclosure secured thereto and provided with an ingress-aperture, a slide-door partially covering such aperture normally, and a partition within the inclosure 115 extending above such aperture to provide a receptacle for sugar or the like and a trap against return through such aperture, substantially as set forth.

8. In a fly-exit device, the combination of the screen, the inclosure secured thereto and provided with an ingress-aperture, a slide-door partially covering such ingress-aperture normally, a partition within the inclosure 120 extending above such aperture, an ingress at each side of such inclosure above such partition and provided with a channel having the walls thereof extending inwardly therefrom, a leadway extending outwardly from each of the 125 ingress-openings at the sides of the inclosure, and an exit at the top of such inclosure, substantially as set forth.

9. In a fly-exit device, the combination of the screen, the inclosure comprising the closed 130 bottom and front and sides and secured to the screen and provided with the ingress-openings at the sides thereof and channels having the walls thereof extending inwardly there-

from, the leadways to such ingress-openings, the exit at the top of such inclosure, and the slide-door and aperture whereby access may be had to insert bait and to remove debris from such inclosure, substantially as set forth.

10. In a fly-exit device, the combination of the screen, the inclosure having the exit at the top and the ingress-openings at the bottom thereof, and leadways connected at the ingress-openings and provided with sliding end extensions whereby the leadways are adjusted to extend to the edges of screens of differing widths, substantially as set forth.

11. In a fly-exit device, the combination of the screen, the inclosure C provided with the partition H and ingress I and door G, the ingress-channels F F at the sides of the inclosure, the leadways D D' connecting with said ingress-channels, and the exit E, substantially as shown and described.

In testimony whereof I affix my signature in presence of two witnesses.
